UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

DRILL SHARPENER.

1,405,084.

Specification of Letters Patent. Patented Jan. 31, 1922.

Application filed May 6, 1919. Serial No. 295,061.

To all whom it may concern:

Be it known that I, WADE H. WINEMAN, a citizen of the United States, residing at Chicago, in the county of Cook, and State of Illinois, have invented certain new and useful Improvements in Drill Sharpeners, of which the following is a full, clear, and exact specification.

My invention relates to drill sharpeners, and more particularly to the upsetting mechanism mounted thereon, the principal objects of the present invention being to provide a new and improved means for alining the vise, dolly holder, and pneumatic hammer, for retaining the dolly in place, and for directing the exhaust of fluid from the pneumatic hammer to the interior of the drill sharpener frame.

Certain embodiments which my invention may assume in practice are illustrated in the accompanying drawings.

In these drawings,—

Fig. 1 is a side elevation of a part of a drill sharpener embodying one form of my improved upsetting mechanism.

Fig. 2 is a plan view of the dolly holder and dolly with the cover or upper guide removed.

Fig. 3 is a front elevation of the dolly and dolly guide, taken substantially on the line 3—3 of Fig. 1.

Fig. 4 is a longitudinal section of the hammer, dolly holder, and vise, illustrating the alining means and a modification of the hammer.

Fig. 5 is a plan view thereof.

Fig. 6 is a diagram subsequently referred to in the specification.

In these illustrative constructions, I have shown a drill sharpener having a base or frame 1, a vertical swaging hammer 2 operated by fluid pressure and controlled by a lever (not shown), a pinning hammer 3 and tool 4, a vise 5 for clamping the work during the upsetting operation, an upsetting hammer 7, and a lever 8 which preferably controls both the upsetting hammer and the vise. The fluid pressure for operating the different parts of the drill sharpener is taken from a pipe 9 through an oiling mechanism 10 which adds a lubricant to the pressure fluid, and through an upright pipe 11 from which it is distributed to the pinning hammer 3 through a pipe 12, to the upset-

ting hammer 7 through a valve box 13 and pipe 14 and to the vise operating mechanism through the valve box 13 and a port (not shown) to a cylinder 15 in which a piston is reciprocated for controlling the vise. The pressure fluid for the hammer 2 is preferably conducted by a pipe extending through the frame 1 from the oiling mechanism 10.

As is clearly shown in Fig. 4, the pneumatic upsetting hammer 7, the dolly guide 16, and the lower jaw 6 of the vise 5 are preferably mounted on a single base plate 17 which is bolted to the frame 1 by bolts 18 passed through holes 18' in a flange 19 cast integral with the base plate 17. This construction gives several material advantages, as follows: The cylinder, piston, dolly, and lower vise jaw may be removed as a unit; the piston and dolly are always in proper alinement; the lower vise jaw is easily removable; and the pressure of the upper vise jaw on the work or on the lower jaw will reinforce the holding action of the bolts 18 so as to insure that the upsetting mechanism is held rigidly in place during the upsetting operation.

The exhaust from the hammer may be conducted by a pipe 20 (see Fig. 1) to the interior of the frame, but preferably it is conducted through a passage 21 cored in the cylinder. It will be noted that this preferred construction lightens the machine, and reduces the time and cost of installation and repair. The upsetting hammer 7 may be held rigidly to the base 17 by bolts 22 passed through lugs 23 formed on the latter and lugs 24 formed either on the wall of the cylinder (Fig. 1) or on one cylinder head (Fig. 5).

The lower semi-cylindrical vise jaw 6 is preferably formed with a dove-tailed collar 25 extending around the curved side thereof (Figs. 4 and 5) and is held in a mating dove-tail groove in the base plate 17 by a bolt 26 which is threaded into a hole extending through the base plate 17 in such a manner that the front end of the bolt may be forced into a depression 27 formed in the collar of the jaw 6, as is clearly shown. A lock nut 28 keeps the bolt 26 from turning and so insures the proper alinement of the work held against the lower jaw, and a dolly 29. By this arrangement the parts are

held in solid relation very securely and since the point or area of application of force (i. e. the point of area of contact) between the bolt 26 and the vise jaw 6 lies within the 5 space which is included within the peripheral surface of the bolt produced and the force is applied in a direction parallel to the axis of the bolt, it will be obvious that a very solid construction must result as, for 10 the jaw to loosen it is necessary for all the threads on the bolt to yield. It will also be noted that the bolt, being supported by its threaded socket, is supported at all points around a cylindrical surface and so is supported among others, by points in a transverse plane so disposed that a triangle whose apices they form will surround the line parallel to the axis of the bolt and passing through the point of application of force to 15 the jaw. This will be more clearly understood by referring to the diagram which constitutes Figure 6 of the drawings. It is possible to consider the bolt whose threads are supported all the way around as stated, 20 as supported among other points by points C, D and E, which points lie between the circles A and B, i. e. the root and outside circles of the thread on the bolt 26. It will be noted that planes parallel to the axis of 25 the bolt and whose traces on the drawing will coincide with the lines C—D, D—E and E—C, enclose a prism within which the area G constituting the contact area between the bolt 26 and the die 6 will lie, and it will 30 be noted that these three points, C, D and E are so disposed relative to the axis F that no plane including the axis F can be drawn so as to have all three points on the same side of it. It will be apparent since the 35 bolt 26 is supported as shown that there will be no tendency for the jaws to become loose unless all the threads yield and that there can be no possible bending, as might occur with a member engaging the jaw only outside 40 of the means which holds it in position.

This dolly may be formed with a square body and a conical head, as is common construction, the body, in the form of my improvement herein shown, being reciprocatively mounted in a dolly guide 16 comprising a base 30 and side walls 31 formed in the base plate 17, and a cover 32 having depending flanges 33, the cover being hinged, as is shown at 34, to a boss 35 cast integral 45 with the base plate 17. This cover 32 may be swung out of the way to permit the easy removal of the dolly, or it may be securely held against the side walls 31 by springs 36 pivoted, as shown at 37, to the base plate 17 50 and having hooked ends 38 adapted to slide over the sides of an M-shaped projection on the cover 32 to the central depression therein. The springs yield readily to a pull or to a pressure tending to force the springs 55 onto or off from the projection to hold the

cover in place or to permit the cover to be swung back for changing dollies.

Cooperating with the dolly to return the latter to a retracted position free from the work and the movable vise jaw, are springs 70 39 which carry on their front ends hooks 40 adapted to snap into depressions 41 in the dolly block, and which carry on their opposite ends suitable means, such as eyes 42, whereby these ends may be retained in a 75 fixed position relative to the dolly holder. In the form of my improvement shown herein, these eyes 42 encircle the heads of bolts 22. To provide the necessary clearance for the movement of the hooked ends 40 in the 80 sides of the dolly holder or guide 30, the side walls 31 and the depending flanges of the cover 32 are spaced apart, as is shown at 43, except at their front ends 44, where the side walls and flanges contact to hold the cover 85 and base in their proper spaced relation.

Attention is directed to the fact that the lower vise jaw 6 is easily removed by withdrawing the bolt 26 from contact with the jaw, sliding the jaw rearwardly for a short 90 distance (about a quarter of an inch), and then lifting this jaw free from the plate 17. When replacing the jaw or when inserting another one, the order of these steps is just reversed. If the work should not be properly done due to an improper alinement of the upsetting mechanism, the plate 17 with all the parts that need to be alined are removed as a unit and the proper alinement may be given the elements of the unit on a 100 bench where the parts will be most accessible. If the operator should attempt to adjust the parts properly when they are mounted on the sharpener frame, the relative position of the upper vise jaw, upsetting 105 hammer, and vertical hammer render a proper adjustment almost, if not entirely, impossible. It should further be noted that the vise is always clamped onto the work before the upsetting hammer is set into operation, and since the pressure exerted by the vise operating mechanism often reaches 100,000 pounds, this pressure alone is sufficient to retain the upsetting unit in place, and when taken with the holding power of 110 the bolts it will be seen that the drill sharpener will never be subjected to a racking or vibration due to an improper movement of the upsetting hammer, dolly guide, or lower vise jaw, or to loose connections.

In the form of my improved dolly holder herein shown, it will be noted that the parts are strong and durable, that no adjustment of the parts is necessary, that no tools of any kind are required, and that the springs 125 hold the cover against rattling and shaking when the hammer is operated. The dollies may be easily interchanged or the working face of a dolly inspected without necessitating the removal and the possible misplacing 130

of parts of the dolly holder, it being apparent that all of these parts are connected directly or indirectly to the base plate 17.

While I have herein shown and described, for the purpose of illustration, certain specific forms of the invention, it is to be understood that the same have been chosen for illustrative purposes only, and that extensive deviations may be made from the disclosed forms thereof without departing from the spirit of the invention.

What I claim as new and desire to secure by Letters Patent is:

1. In a drill sharpener, an integral member comprising a base plate, a vise jaw retainer, means carried by said base plate for holding a pneumatic cylinder in fixed relation thereto, and a cylinder exhaust passage formed in said base plate. 70
2. In a drill sharpener, an integral member comprising a base plate, a dolly guide, means carried by said base plate for holding a pneumatic cylinder in fixed relation thereto, and a cylinder exhaust passage formed in said base plate. 75
3. In a drill sharpener, an integral member comprising a base plate, a dolly guide, a vise jaw retainer, means carried by said base plate for holding a pneumatic cylinder in fixed relation thereto, and a cylinder exhaust passage formed in said base. 80
4. In a drill sharpener, the combination comprising a base plate having a dovetailed recess formed thereon, a jaw having a mating dovetailed projection, and means for holding said projection and plate in mated relation comprising a peripherally supported member engaging said jaw at a point within the periphery of said member produced. 85
5. In a drill sharpener, the combination comprising a base plate having a dovetailed recess formed therein, a jaw having a mating dovetailed projection, and means for holding said projection and plate in mated relation comprising a member engaging said jaw and supported at at least three points spaced from the axis of said member and so disposed that all three points are on the same side of no plane that can be drawn to include the axis of said member, said member engaging said jaw at a point lying within the space enclosed by the three planes which can be drawn parallel to said axis and each including a pair of said points. 90
6. In a drill sharpener, the combination comprising a base plate having a dovetailed recess formed therein, a jaw having a dovetailed projection, and a bolt adjustably mounted in said base plate for holding said projection and recess in mated relation, said bolt engaging said jaw at a point such that a line parallel to the axis of the bolt and passing through said point will lie within the periphery of said bolt. 95
7. In a drill sharpener, a dolly, dolly guiding means comprising cooperating guiding members, and resilient means extending between said members and operative to maintain them in dolly guiding relation. 100
8. In a drill sharpener, a dolly, dolly guiding means comprising cooperating hinged guiding members, and resilient means extending between said members and operative to maintain them in dolly guiding relation. 105
9. In a drill sharpener, a dolly, dolly guiding means comprising cooperating guiding members, and resilient means mounted on one of said members and cooperating with the other to retain said members normally in dolly guiding relation. 110
10. In a drill sharpener, the combination comprising a dolly, a base plate, a dolly guide having a base and side walls formed thereon, and a cover hingedly mounted on said base plate and adapted to cooperate with said base to hold said dolly. 115
11. In a drill sharpener, the combination comprising a dolly, a base plate, a dolly guide having a base and side walls formed thereon, a cover hingedly mounted on said base plate and adapted to cooperate with said base to hold said dolly, and resilient means for holding said cover against said base. 120
12. In a drill sharpener, the combination comprising a dolly, a base plate, a dolly guide having a base and side walls formed thereon, a cover mounted on said base plate and adapted to cooperate with said base to hold said dolly, and resilient means for holding said cover against said base. 125
13. In a drill sharpener, the combination comprising a dolly, a base plate, a dolly guide having a base and side walls formed thereon, a cover mounted on said base plate and adapted to cooperate with said base to hold said dolly, and resilient means hinged to said base for holding said cover against said base. 130
14. In a drill sharpener, the combination comprising a dolly, a base plate, a dolly guide having a base and side walls formed thereon, a cover hingedly mounted on said base plate and adapted to cooperate with said base to hold said dolly, and hinged resilient means for holding said plate against said base. 135
15. In a drill sharpener, a dolly, resilient means for retaining the same in a position retracted from its work, and dolly guiding means comprising cooperating dolly guiding members and resilient means extending between said members and normally maintaining them in dolly guiding relation. 140
16. In a drill sharpener, a dolly, dolly guiding means comprising cooperating hinged dolly guiding members, resilient means mounted on one of said members and cooperating with the other thereof to hold

said members in dolly guiding relation, and means for retaining said dolly in a position out of contact with the work comprising resilient means cooperating with said dolly 5 at the rear of said first mentioned resilient means.

17. In a drill sharpener, the combination comprising a dolly guide having a base plate and side walls, a cover for said guide 10 having flanges thereon, means for holding said side walls and flanges spaced for a part of their length, a dolly, and means passing through the space between said walls and flanges and engaging the dolly for normally holding the dolly retracted.

18. In a drill sharpener, the combination comprising a base plate, a dolly guide having a base formed thereon, a hinged cover for said guide, projections on said cover, 20 and resilient means cooperating with said projections to hold said cover on said base.

19. In a drill sharpener, the combination comprising a base plate, a dolly guide having a base formed thereon, a cover for said 25 guide, projections on said cover, and resilient means cooperating with said projections to hold said cover on said base.

20. In a drill sharpener, the combination comprising a base plate, a dolly guide having a base formed thereon, a cover for said 30 guide, a substantially M-shaped projection on said cover, and resilient means cooperating with said projection to hold said cover on said base.

21. In a drill sharpener, the combination comprising a base plate, a dolly guide mounted thereon, a dolly having a retracted 35 and a forward position in said guide, a hinged cover for said guide, resilient means for holding said cover on said guide, and resilient means for holding said dolly in the retracted position.

22. In a drill sharpener, the combination comprising a base plate, a dolly guide 45 mounted thereon, a hinged cover for said guide, resilient means for holding said cover on said guide, a dolly having a retracted and a forward position in said guide, a pneumatic hammer attached to said plate, 50 and resilient means attached to said hammer and dolly for holding said dolly in the retracted position.

23. In a drill sharpener, the combination comprising a base plate, a dolly guide

mounted thereon, a hinged cover for said 55 guide, resilient means hinged to said plate for holding said cover on said guide, a dolly having a retracted and a forward position in said guide, a pneumatic hammer attached to said plate, and resilient means attached 60 to said hammer and dolly for holding said dolly in a retracted position.

24. In a drill sharpener, a base plate having a dove-tailed recess formed therein, a 65 vise jaw having a mating dove-tailed projection formed thereon, a dolly guide base formed in said plate, a bolt adjustably mounted in said plate beneath said base and adapted to hold said projection and recessed plate in mated relation, a hinged cover for 70 said guide, and resilient means hingedly mounted on the plate for retaining the cover on said guide.

25. In a drill sharpener, a base plate having a dove-tailed recess formed therein, a 75 vise jaw having a mating dove-tailed projection formed thereon, a dolly guide base formed in said plate, a bolt adjustably mounted in said plate beneath said base and adapted to hold said projection and recessed 80 plate in mated relation, a hinged cover for said guide, resilient means hingedly mounted on the plate for retaining the cover on said guide, a pneumatic hammer held in fixed relation to the plate, a dolly in said 85 guide, and a resilient connection between said hammer and said dolly.

26. In a drill sharpener, a plate, a hammer piston, a dolly, a vise jaw, and means mounted on said plate for holding said piston, dolly, and jaw in alinement, said means including a hinged dolly guide cover and means for detachably retaining the jaw.

27. In a drill sharpener, an upsetting mechanism comprising a base plate having 95 integral therewith a dolly guide, and fluid pressure operated means cooperating therewith for retaining said base plate and dolly guide in a fixed position.

28. In a drill sharpener, a member comprising a base plate and a dolly guide, a pneumatic tool secured thereto, and fluid pressure operated means cooperating with said member to retain the same in fixed position irrespective of the operation of said 105 pneumatic tool.

In testimony whereof I affix my signature.
WADE H. WINEMAN.
